United States Patent Office

Des. 180,366
Patented May 28, 1957

180,366

STAND

Dorothy M. S. Hitchins, Philadelphia, Pa.

Application September 6, 1955, Serial No. 37,793

Term of patent 3½ years

(Cl. D80—10)

I claim:

The ornamental design for a stand, as shown.
